UNITED STATES PATENT OFFICE

JAMES S. REID, OF CLEVELAND, OHIO, ASSIGNOR, BY MESNE ASSIGNMENTS, TO EATON MANUFACTURING COMPANY, OF CLEVELAND, OHIO, A CORPORATION OF OHIO

CLOSURE

Application filed May 25, 1928. Serial No. 280,543.

This invention relates to improvements in closures such as are used for closing the crank receiving openings of automobile radiator aprons.

5 The openings to be closed in these aprons are of circular shape and it has been customary to provide similarly shaped closures for said openings, the closures being detachably connected to said aprons by rotary 10 movement of said closures. In some instances, said aprons have forwardly extending annular beads or ridges around said openings, provided either for ornamental purposes or otherwise, and the closures have 15 engaged said aprons just outside of said beads or ridges, thereby becoming sort of interlocked therewith. As a result of this interlocking and the necessity for rotating the closure in applying and removing the 20 same, said beads or ridges have been confined or limited to annular shapes.

It is therefore the general object of the present invention to provide an improved closure for the openings of objects of the 25 sort above mentioned, which closure permits said objects to be provided around said openings with forwardly extending beads or ridges of non-annular form, such as oval, the closure being nevertheless capable of detachable connection to said objects by rotary movement of said closure.

A more specific object of the invention is the provision of an improved closure of the character described which consists primarily 35 of two parts, a cover part, preferably of ornamental character, and a locking part adapted to be detachably connected to the radiator apron or other object having the opening to be closed, said parts having a threaded connection therebetween which prevents complete separation or disassembly thereof but which permits movement of the cover part toward and from the locking part 40 so that said cover part can be moved into engagement with the radiator apron or other object after the locking part has been connected thereto and can be moved out of such engagement to enable rotary movement to 45 be imparted to the locking part to discon-

nect it from said radiator apron or other object.

Further objects of the invention are in part obvious and in part will appear more in detail hereinafter.

55

In the drawing, in which is illustrated one suitable embodiment of the invention, Fig. 1 is a central vertical sectional view of the closure detachably connected to the filler neck of an automobile radiator apron or 60 other object; Fig. 2 is a similar view but showing the cover part of the closure separated from the locking part thereof so as to enable the closure to be rotated to remove it; Fig. 3 is a cross sectional view of the 65 closure on the lines 3—3, Figs. 1 and 2; Fig. 4 is a top plan view of the closure; Fig. 5 is a cross sectional view of the closure on the line 5—5, Fig. 2; Fig. 6 is a top plan view of the filler neck to which the closure is adapted 70 to be connected; and Fig. 7 is a vertical sectional view thereof on the line 7—7, Fig. 6.

Referring to said drawing, 1 represents an automobile radiator apron or other object having an opening to be closed, a tubular 75 neck 2 being suitably mounted in said opening. Said neck is provided at its upper end with an inwardly extending annular flange 3 substantially flush with the apron 1, said flange terminating in a depending flange 4. 80 At two diametrically opposite points, parts of flanges 3 and 4 are cut away to provide two passage-ways 5 for the closure locking fingers, as will later appear. The cutting away of said flange parts provides two depending 85 flange portions 4 of substantially semi-circular form, and the lower edges of said flange portions are inclined to form two cam surfaces 6 with which the closure locking fingers cooperate in effecting a detachable connection therewith. Preferably and as shown, each cam surface is provided at its rear end 90 with a dwell or seat 7 to receive a closure locking finger when the closure is in fully locked position on the filler neck, and each 95 flange portion 4 is provided adjacent its dwell or seat with a depending projection 8 to limit rotary movement of the closure, as will be readily understood. For purposes of 100 ornamentation or otherwise, the apron 1 is

provided around said neck with a forwardly extending bead or ridge 10, which bead or ridge may be of any suitable shape, annular or otherwise, being here shown as of oval 5 shape.

The closure for the opening of the filler neck includes two main parts, a locking part adapted to be detachably connected to the filler neck and a cover part, preferably ornamental in character, the two parts having a threaded connection therebetween which permits of relative movement of either part toward and from the other but which prevents complete separation or disassembly thereof.

15 The locking part includes a cup-shaped member having a cylindrical side portion 15 and a circular bottom portion 16, said bottom portion being provided with a circular depression 17 forming a correspondingly 20 shaped recess. Suitably secured within said recess, such as by a crimping operation, is the circular base portion 18 of the closure locking member, said base portion being provided with two diametrically opposed locking fingers 20 which extend upwardly and outwardly through openings 21 in the cylindrical side wall 15 of the cup-shaped member. The projecting ends 22 of said fingers are adapted for cooperative engagement with the cam surfaces 25 6 of the filler neck, as will later appear.

The upper end of the cylindrical side portion 15 of the cup-shaped member merges into an outwardly extending annular flange 23 terminating in an upwardly extending 30 marginal portion 26. Seating upon said outwardly extending portion 23 is a diaphragm member 27 on which seats a disc 28 suitably slotted or sheared to provide in the marginal portion thereof four circumferentially arranged upstanding arms 29. Said diaphragm member and said disc are maintained in such seated position by bending inwardly the upper end portion 32 of the marginal portion 26 of the cup-shaped member, as clearly indicated in Figs. 1 and 2.

The ornamental cover part of the closure includes a top member having a dome-shaped portion 35 and a depending skirt portion 36 bent inwardly into confining engagement 40 with the depending marginal portion 37 of a plate member 38 substantially covering the bottom of the dome-shaped portion 35 of the top member. The central portion of said plate member is provided with four circumferentially arranged slots to receive the upstanding arms 29 of the locking part of the closure, said plate member being prevented from escaping from said arms by a disc 39 welded or otherwise permanently mounted 45 upon the upper ends of said arms, which ends are provided with shoulders 40 upon which said disc seats, as shown in Fig. 1.

The disc 39 is provided with a central opening in which is threaded a depending stem 45 55 provided at its upper end with a suitable

head 46 lying within a central opening in the dome-shaped portion 35 of the top member. Said head has secured thereon a suitable knob 47 to which rotary movement is imparted when it is desired to rotate the stem 45 to effect relative movement of the cover and locking parts of the closure. The lower end portion of said stem extends through a central opening in the plate member 38 and has secured on its lower end a lock ring 50 which prevents the stem from being removed from the plate member 38 and the disc 39.

To secure the closure to the radiator apron or other object 1, the cover and locking parts of the closure must be in separated relation, as shown in Fig. 2, which separation is effected by counter-clockwise rotation of the threaded stem 45 through its knob 47. The projecting ends 22 of the fingers 20 of the closure locking part are then inserted 85 through the passage-ways 5 of the filler neck, after which clockwise rotary movement is imparted to said locking part to cause said finger portions to ride down the cam surfaces 6 until they reach the dwells 7 therein 90 adjacent the stop projections 8. The cover part of the closure of course rotates with the locking part thereof, due to the extension of the arms 29 through the plate member 38.

After the closure locking part has been thus connected to said filler neck, the closure cover part is moved toward said locking part into engagement or substantial engagement with the radiator apron or other object 1. Such movement is effected by rotating the threaded stem 45 in a clockwise direction, the cover part moving from the position shown in Fig. 2 to the position shown in Fig. 1 wherein its skirt or marginal portions 36, 37 engage or substantially engage the apron 1 just outside of the oval bead or ridge 10.

To remove the closure, counter-clockwise rotation is imparted to the threaded stem 45, which causes the cover part of the closure to retreat or move away from the locking part thereof, thereby freeing the depending skirt portions 36, 37 of said cover part from any interlocking connection with the bead or ridge 10 of the apron 1. After the cover part has been thus separated from the locking part, both parts are rotated in a counter-clockwise direction, which causes the finger portions 22 of the locking part to leave the dwells 7 and ride down the cam surfaces 6 until they reach the passage-ways 5, at which time the closure can be readily removed from the filler neck, as will be readily understood.

If desired, and as shown, a gasket 52 of cork or other yielding material may be interposed between the top flange 3 of the filler neck and the outwardly extending flange 23 of the closure locking part, said gasket effecting a tighter seal of the filler neck opening.

What I claim is:

1. A closure, comprising a locking part 130

provided with an outstanding arm and a cover part provided with a member having a slot through which said arm extends, means on the free end of said arm for preventing escape of said cover part member, said escape preventing means being provided with a threaded opening, and a threaded member carried by said cover part and threaded in said opening, whereby rotation of said threaded member causes said cover part to move without rotation toward or from said locking part.

2. A closure, comprising a locking part provided with an outstanding arm and a cover part provided with a member having a slot through which said arm extends, means on the free end of said arm for preventing escape of said cover part member, said escape preventing means being provided with a threaded opening, and a threaded member carried by said cover part and threaded in said opening, whereby rotation of said threaded member causes said cover part to move without rotation toward or from said locking part, and means carried by said threaded member for preventing its withdrawal from said threaded opening.

3. A closure, comprising a locking part provided with an outstanding arm and a cover part provided with separated inner and outer walls, said outer wall having an aperture and said inner wall having a slot to receive said arm, a disc mounted upon the free end of said arm to prevent escape of said inner wall from said arm, said disc being provided with a threaded opening, a threaded member carried by said cover part and threaded in the opening of said disc, said threaded member being provided at its outer end with a manipulating head lying within the aperture of said outer wall, the parts being so constructed and arranged that rotation of said threaded member effects movement without rotation of said cover part toward or from said locking part.

4. A closure, comprising a locking part provided with an outstanding arm and a cover part provided with separated inner and outer walls, said outer wall having an aperture and said inner wall having an opening and a slot to receive said arm, a disc mounted upon the free end of said arm, said disc being provided with a threaded opening, a threaded member carried by said cover part and threaded in the opening of said disc, said threaded member being provided at its outer end with a manipulating head lying within the aperture of said outer wall, the inner end portion of said threaded member extending through the opening of said inner wall and being provided inside said wall with means for preventing withdrawal of said threaded member from the openings in said inner wall and said disc, the parts being so constructed and arranged that rotation of

said threaded member effects movement without rotation of said cover part toward or from said locking part.

In testimony whereof I hereby affix my signature.

JAMES S. REID.
